DIVER CONTROLLED SALVAGE BELL

Carl M. Zoll, Dundalk, Md., assignor to Universal
Hydraulic Stress Equalizer, Inc., Dundalk,
Md.

Application July 15, 1941, Serial No. 402,533

12 Claims. (Cl. 61—69)

This invention relates to diving bells and has special reference to an electro-hydraulically operated diving bell preferably called a diver controlled salvage bell.

In the salvaging of ships, as by the apparatus shown and described in my application for patent for Hydraulic stress equalizer, filed April 23, 1941, Serial Number 389,974, it is necessary to engage hoisting hooks with the hull of a sunken ship and it is often necessary to cut holes in the ship's sides in order to provide for such engagement of the hooks. While for certain more or less shallow depths of water such operations may be performed by a diver in an ordinary diving suit, for greater depths the strain on the diver's physique makes it difficult for him to work but a short time and it is impossible for him to perform any work or even descend below a very limited depth. Ordinary diving bells suspended from a tender at the surface may, it is true, carry a diver to depths greater than those in which he can live when dressed in the usual rubber suit. However, ordinary diving bells so supported are very difficult to control from the tender and are subject to movement both by under water currents and by wave action on the tender. The diver in such a bell has no means for accurately controlling the bell movements and cannot therefore work efficiently.

It is one principal object of the present invention to provide improved diving bell apparatus which may be electro-magnetically attached to a sunken hull at the will of the diver and while so attached may be caused by the diver to perform three dimensional movements. That is, the diver may cause the bell to move up and down, toward and from the sunken ship and right and left along the ship.

A second important object of the invention is to provide hydraulic mechanisms controllable by the diver in the bell for effecting such movements.

A third important object of the invention is to provide an improved diving bell apparatus whereby the bell may be operated readily at depths greater than those at which a diver can work in an ordinary suit.

In using a diving bell in such depths as those at which a diver can work in a rubber suit it sometimes happens that it is desirable for the diver to leave the bell and return thereto.

It is a fourth important object of the invention to provide an improved diving bell provided with means whereby a diver may leave and enter the bell, while the latter is under water, without

flooding the bell or changing the pressure in the bell.

It is sometimes desirable to leave and enter such a bell at depths at which the pressure on the diver is sufficiently great enough to produce what is known as "bends" if the pressure is too rapidly reduced. In using an ordinary dress the pressure at any but very shallow depths is gradually reduced by raising the diver very slowly to the surface. This takes much time and, when the water is cold, the diver reaches the surface in a thoroughly chilled and exhausted condition.

It is a fifth important object of the invention to provide a novel form of diving bell having an exit and entrance chamber for underwater use, the chamber being associated with means whereby the pressure therein due to the depth at which the bell is being used may be so controlled after a diver enters from the outside that it may be reduced as slowly as desired thereby preventing "bends" and enabling the diver to attain normal air pressure without exposure to chilling.

A sixth important object of the invention is to provide a novel bell construction having an exit and entry chamber in which the pressure may be controlled both by a diver in the chamber and by a diver in the body of the bell and provided with a window between the chamber and bell body so that a diver in the latter can control the pressure in the chamber in case the diver in the chamber is physically unable to attend to the control himself.

With the above and other objects in view, the invention consists in general of certain novel details of construction and combinations of parts hereinafter fully described, illustrated in the accompanying drawings and particularly pointed out in the appended claims.

In the accompanying drawings like characters of reference indicate like parts in the several views, and:

Figure 1 is a side elevation of the apparatus and showing the side facing away from the ship when the device is in use.

Figure 2 is a section on the line 2—2 of Figure 1.

Figure 3 is a section on the line 3—3 of Figure 1.

Figure 4 is a section on the line 4—4 of Figure 3.

Figure 5 is a section on the line 5—5 of Figure 1.

Figure 6 is a view partly in elevation and partly in section on the line 6—6 of Figure 5, the view

showing only the bell supporting frame and being taken from the side opposite Figure 1.

Figure 7 is an enlarged section through the bell and chamber on the line 7—7 of Figure 1.

Figure 8 is a detail vertical section taken through a portion of the bell and decompression chamber used herein, the view showing the water valve for the decompression chamber.

Figure 9 is a view similar to Figure 8 but showing the air exhaust and inlet valve for the chamber.

Figure 10 is a similar view showing the decompression valve and its control.

Figure 11 is a detail vertical section showing the arrangement of a bull's-eye window in the door between the bell body and chamber.

Figure 12 is a face view of the control board within the bell body and also disclosing the oil pump and oil sump in said bell body.

Figure 13 is a view showing the bell and socket joint for mounting an oxy-acetylene or other similar blow-torch in the bell body wall.

Figure 14 is a diagram illustrating the several jacks and carriages used in the invention and the arrangement of the piping and control valves.

Figure 15 is a schematic view of one of said control valves.

Figure 16 is a schematic view of an auxiliary device used in tilting the bell and its supporting parts for work under an overhanging side of a ship.

Figure 17 is a detail partly in elevation and partly in section and showing the joint arrangement for certain jack sections used in this invention.

In the form of the invention here disclosed there is provided at each end of the device an end member indicated generally at 10 and which may be of any desired vertical length. Each member 10 has its upper and lower ends of rectangular tubular form and in the top and bottom of each member 10 is fixed a clamp casting 11 having a bore 12 extending therethrough and split to provide a pair of jaws 13 which may be drawn towards each other by clamping bolts 14. In each bore 12 is slidably fitted a tubular bar or arm 15. Associated with each arm 15 is an electro-magnet 16 of the waterproof type and of such strength that the four magnets thus provided will properly support the entire apparatus when energized and in contact with the hull of a steel ship. Each magnet 16 is provided with a centrally disposed shank 17 having a ball at its free end fitting in a socket 18 formed at the end of the respective arm 15. Thus each magnet is connected to its arm by a ball-and-socket joint so that the magnet has universal swinging movement with respect to the arm. A conductor cable 19 leads from the magnet through its arm and to a control in the bell as will be presently described. By means of this construction the bars or arms 15 may be adjusted as desired and then secured in adjusted positions by tightening the bolts 14. Also the universal joints permit the magnets to take positions conforming to the shape of the hull of a ship.

Between the upper and lower sections of each member 10 is fixed a transverse rectangular tubular member indicated generally at 20. The outer side of each member 20 is closed by a plate 21 which extends above and below the member 20 and is fixed, as by welding or riveting to the member 10 to assist in bracing the parts. The inner side of the member 20 is similarly braced to the member 10 by a pair of plates 22 which

have spaced parallel edges to provide a slot 24 extending longitudinally from one end to the other of the member 20. The plates 21 and 22 are connected by end plates 23. In each member 20 is a carriage 24 slotted to receive grooved wheels 25 and supported in the slots by shafts or pins 26. The upper and lower walls 27 of the member 20 are provided with half-round tracks 28 on which the wheels 25 run. There are two pairs of upper wheels 25, the pairs being spaced longitudinally of the member 20 and the lower wheels 25 are similarly arranged. Thus the carriage 24 may roll freely from a position near one end of the member 20 to a position near the other end of said member but is prevented from tilting in any direction. A shank 29 is formed integrally with the carriage and extends through the slot 24 for purposes presently to be described. Arranged on the longitudinal axis of each member 20 is a pair of telescopic hydraulic jacks 30 each consisting of a series of tubular members slidable one within another. One end of each jack is fixed against a plate 23 while the other end is fixed against a corresponding side of the carriage 24 and into the latter end opens a supply passage 31 which extends through the carriage 24 and shank 29. In Figure 3 the carriage 24 has been shown in its furthest position to the right or toward a ship. If now oil be supplied to the right hand jack 30 and allowed to escape from the left hand jack the former will expand and the latter collapse so that the carriage will move to the left or away from the ship. Obviously by checking the supply and exhaust the carriage may be stopped in any desired position and, should the carriage be away from its present position, it may be moved to the right by supplying oil to the left hand jack 30 and exhausting the right hand jack.

In connection with the members 10 and 20 there is provided a rectangular frame positioned between the said members and having end members indicated in general at 32, and top and bottom members indicated in general at 33. The end members 32 are of rectangular tubular form and the outer wall of each member is provided with a slot 34 through which extends the shank 29. Within the member 32 the shank 29 is provided with an integral carriage 35, the carriages 24 and 35 thus forming a single rigid structure which may move in and out along the member 20 but cannot move vertically. The carriage 35 is slotted to receive grooved rollers 36 as in the carriage 24 but in this instance the rollers are disposed to bear laterally on pairs of half-round tracks 37 carried by the outer and inner walls of the member 32. The member 32 is closed at its upper and lower ends by walls 38 and between these walls and the carriage 35 extend telescopic hydraulic jacks 39. The jacks 39 are similar to the jacks 30 but, since the members 32 are longer than the members 20 in order to give required vertical movement to the carriages 35, the jacks 39 are arranged to give the required greater movement of the members 32. This may be done, as shown in Figure 5, by making the jack sections longer or the number of sections may be increased as will be understood presently from the description of the members 33. Each member 32 has its inner wall provided with a longitudinal slot 40 and a pipe connection boss 41 is formed on the carriage 35 and extends through the slot 40. The jacks 39 are connected by passages 42 extending through this boss to flexible oil pipes 43, the passages 31 also being continued

through the carriage 35 and boss 41 and connected to flexible oil pipes 44. The operation of the jacks 39 is similar to that of the jacks 30. That is, when it is desired to raise the frame relative to the carriage 35 oil is fed into the upper jacks 39 and allowed to flow from the lower jacks and when it is desired to lower the frame oil passes from the upper jacks and enters the lower jacks.

Each of the frame members 33 is of rectangular tubular form and each is provided with a longitudinal slot 45 in its inner wall, the slots extending from one member 32 to the other. Movable longitudinally in each member 33 is a carriage 46 supporting shafts or trunnions 47 whereon are mounted grooved wheels 48. The lower wall of each member 33 is provided with half-round tracks 49 on which the wheels 48 run. Between each end of each member 33 and its carriage 46 is a telescopic hydraulic jack 50 and these jacks act to move the carriages to the right and left in a manner corresponding to the action of the jacks 30 and 39, oil passages 51 being provided in the carriages 46 for the supply and exhaust of oil. The carriages 46 have neck portions 52 and these portions form seats for the ends of a bell body 53 which is of substantially circular cross-section and is provided with semi-spherical ends the better to resist water pressure at the depths to which the bell may descend. The necks 52 pass through the slots 45 and, by the action of the jacks 50, the bell body may be moved right and left.

It has been stated that the telescopic jacks used in this invention each consists of a series of sections. In order to illustrate the manner in which these sections are slidably connected the connection between two of these joints is shown typically in Figure 17. In this figure there is shown one end of an outer section 54 and the interfitting end of an inner section 55. The section 54 is provided with an internal flange or lip 56 fitting closely around the body of the section 55. The inner end of the section 55 is provided with an external flange or lip 57 fitting closely in the section 54. The lips 56 and 57 coact to limit outward movement of the section 55 with respect to the section 54. At its extremity the section 54 is provided with a stuffing-box 58 of the usual type. The section 55 thus has fluid tight connection with the section 54.

The side of the device which faces the ship is shown in Figure 6 and on this side the bell body 53 is provided with suitably disposed bull's-eye ports or windows 59 and flood lights 60 to enable the diver within the bell body to properly observe the sunken ship. Also this side of the bell body carries an oxyacetylene or other torch 61 suitable for underwater work. The manner in which this torch is mounted for swinging movement in any direction within limits is shown in Figure 13. Here the wall of the bell body 53 is shown as provided with an opening 62 in which lies a spherical enlargement 63 formed on the outer tube 64 of the torch, the inner tube being shown at 65. Segments-spherical socket members 66 are fixed on the body wall and embrace those portions of the enlargement or ball 63 which project from the opening 62 and fit closely in said ball. Thus swinging movement of the torch in any direction may be obtained. Suitable packing may be used for rendering the joint water tight as indicated at 67. Also, a hook or other tool 68 may be mounted similarly to the torch for purposes of manipulating the hoisting hook of the aforesaid application and for any

other desirable use. It will further be noted on Figure 6 that the flexible pipes 43 and 44 extend to connecting bosses 69 on the sides of the bell body 53 so that the jacks 30 and 39 may be controlled, by means presently to be described, from within the bell body. A jet nozzle 70 extends downwardly and forwardly from the lower part of the bell body to enable a strong stream of water or air to be directed against the sea bottom to wash accumulated mud or sand away from the ship thus lightening the adhesion of the ship to the bottom.

On the upper front side of the bell body, as best seen in Figure 1, is a junction box 71 which receives the pipes and electric cables used in supply in air, gas and electricity from the salvage hull or tender to the interior of the bell for the various requirements incident to its use. These instrumentalities include an air inlet 72 for supplying fresh air to the diver or divers and an air outlet 73 for carrying off impure air, a high pressure air supply line 74, an oxygen supply pipe 75 and a gas supply pipe 76 for the torch, a cable 77 for the operating supply conductors and a cable 78 for the telephone and alarm wires.

Fixed to the bell body on the side away from the ship is a chamber structure 79 which is used for entrance to and exit from the bell body and is so constructed and arranged as to be capable of use under water so that a diver clad in a proper diving dress may leave the bell for work that cannot be performed from within the bell and may return and enter the bell body without admitting water therein. To this end the bell body is provided with an opening surrounded by a door frame 80 leading into the chamber 81 of the structure 79. In this frame 80 is fitted a door 82 of the bank vault type so arranged that pressure of air or water in the chamber 81 only urges the door to more tightly seal in the door opening thus preventing entry of water into the bell body when the door is closed. Obviously, whenever there is water in the chamber 81 the door will be closed. This doorway is just above the working floor 83 of the bell body and below this floor is a sump 84 for reception of a supply of oil to be used in the jacks. In the front wall of the structure 79 is a door opening provided with a door 85 similar to the door 82 and, like it, opening away from the bell body so that, with the door 85 closed water pressure on the outside only increases the sealing effect. It is intended to provide locking means such as are used for the doors of water tight bulkheads for these doors but, for the sake of simplicity in the disclosure, such locking means has been indicated at 86 as a single swinging clamp operable from either side of the door. In the door is provided a bull's-eye port or window 87 best shown in Figure 11 and a similar port 88 is provided in the door 85. A water inlet and outlet pipe 89 is fixed in the bottom of the chamber 81 and is provided with a control valve 90 having a stem 91 which extends up towards the top of the chamber 81 and is provided with a hand wheel 92 for operating the valve from within the chamber 81. In order to operate this valve from within the bell body a horizontal shaft or stem 93 is connected to the stem 91 by bevel gearing 94. This shaft extends through a stuffing box 95 into the bell body and is there provided with a hand wheel 96. At the top of the chamber 81 is an air inlet and outlet pipe 97 which passes through the wall of the bell body and is connected to one of the air pipes in the box 71. The pipe 97 carries a valve 98 which has a stem 99 provided with a

hand wheel 100. The stem 99 passes through a stuffing box 101 into the bell body and is there provided with a hand wheel 102. Near the top of the chamber 81 is also a bleeder pipe 103 which extends into the bell body. A valve 104 controls this pipe and has a stem 105 passing through a stuffing box 106 and provided with hand wheels 107 and 108 in the chamber 81 and bell body respectively. The pipe 103 carries, within the bell body, a regulating valve 109 of the type used to control drop in fluid pressure per unit of time, the valve being capable of being set to any desired drop per the time unit. This valve is so positioned within the bell body that it may be observed by a diver in the chamber 81 through the port 87 and by a diver in the bell body. On the door 82 is a plug socket 110 for the telephone line of a diver's helmet. As will now be explained, the chamber 81 not only serves as an entrance and exit chamber but also serves as a decompression chamber. As an example of the use of this chamber 81 let it be supposed that the bell is in 150 feet of water and a diver desires to leave the bell. He puts on his dress, opens the door 82, steps into the chamber 81 and closes and locks the door. Next he opens the valves 90 and 98 to such an extent that water will flow into the chamber and air flow out at such rates that pressure in the chamber will not increase too rapidly for comfort. When the chamber is full of water up to the inlet of the valve 98 the diver closes the latter. Next he closes the valve 90. At this time pressure within the chamber will be equal to that outside the apparatus. The diver, having previously connected his helmet telephone to the socket 110 may now open the door 85 and leave the chamber 81. On his return he first closes and locks the door 85 and opens the sea valve 90. Next he opens the valve 104. Now the arrangement of the valve 109 is such that it controls the speed of flow in either direction, the flow into the chamber 81 being obtained from a pipe 111 leading from the high pressure pipe 74. The valve 109 is set for rapid flow by the diver in the bell body acting, if desired by direction of the diver in chamber 81 over his telephone. Consequently the high air pressure will force the water out through the valve 93. The air pressure in the chamber 81 will now be somewhat greater than the external water pressure and it will be obvious that if this pressure is too rapidly lessened the diver in the chamber 81 will be subject to "bends." Accordingly, before changing the valve 109 to allow flow from the chamber 81 this valve is set for a slow rate of flow that the pressure will drop so gradually that "bends" will not be produced, the valve 104 being closed while the change of the valve 109 is effected. When the valve 104 is again opened air will flow gradually out of the chamber until the pressures within the chamber and bell body will be equalized whereupon the door 82 may be opened and the diver may enter the bell body. It is to be noted that the provision of valve operating means both in the chamber 81 and in the bell body ensures safety since there will always be a diver in the bell body who can observe his companion in the chamber 81 and, if the latter shows signs of distress and is unable to manipulate the valves this may be done by the one in the bell body. It is also to be noted that the provision of this underwater decompression chamber relieves the diver from a slow passage upwards through cold water since the chamber 81 will, as soon as the water is driven out be filled

with air and an electric heater may be provided for warming this air if desired.

In the bell body is located a control board 112. Behind this board are valves 113, 114 and 115 controlling respectively the front and back, the up and down and the right and left jacks 30, 39 and 50. On the floor 83 is a motor driven pump 116 lifting oil through a pipe 117 and supplying to the said valves through a pipe 118. Exhaust from these valves is delivered to the sump 84 through a pipe 119. From these valves lead pipes 44' which communicate with the pipes 44 and thus to the jacks 30; pipes 43' which communicate with the pipes 43 and thus to the jacks 39 and pipes 51' which communicate with the passages 51 and thus to the jacks 50. Taking, for example, the valve 115 as diagrammed in Figures 14 and 15 it will be seen that by rotating the plug 115' through 90° the left pipe 51' will be connected to the outlet pipe 119 and the right hand pipe 51' to the supply pipe 118. Thus these valves will effect movement of the carriages in the desired direction.

On the board 112 are also mounted an air pressure gauge 120, a similar gauge 121 to indicate the pressure in chamber 81 and an oil pressure gauge 122. There are valves 123 and 124 for the oxygen and gas lines, a flood light switch 125, a heater switch 126, a motor switch 127 controlling the circuit wires 128, an alarm switch 129, a light switch 130 and four switches 131 for the four magnets 16. A telephone 132 is carried on the board. Other valves, switches and gauges may be used in this connection as may be found desirable or convenient in the actual operation of the invention.

It often happens that a ship heels over after sinking so that one side forms an overhanging surface too greatly inclined for the apparatus above described to swing to proper position for service if supported from the top as by chains 133 (Figure 1). In such case the auxiliary apparatus shown in Figure 16 will be used. In this figure the ship S has its side s overhanging the sea bottom. A frame 134 suspended by chains 135 has a second frame 136 swinging from its upper edge portion. This frame 136 supports the bell device above described and here indicated in general at B on arms 137 and crossbars 138. Pivoted intermediate its ends to the lower part of the frame 134 is a bent lever 139 carrying at its lower end a roller 140, which bears against the frame 136. To the upper end of the lever 139 is attached a cable 141 led upwards to the salvage ship by a roller 142 carried by a rearward extension of the frame 134. With this arrangement pulling on the cable 141 will bias the lever 139 and the roller 140 will act to swing the lower part of the frame 136 away from the frame 134 until the apparatus B is brought into substantial parallelism to the side s so that the magnets 16 may engage the hull.

In using this bell the divers enter the bell body 53 above water. The bell is then lowered so as to bring it to the desired position close to the side of the sunken vessel, the frame being preferably centered vertical of the members 10 and horizontally of the members 23 and the bell body central between the end members of the frame. This lowering and positioning is directed by one of the divers from the bell body over the telephone. Current is then supplied the magnets which cling to the ship's hull. The bell body may now be adjusted with nicety by manipulation of the valves 113, 114 and 115 until the torch is opposite the

place at which the first hole is to be cut and the hole is cut. When this operation is finished the bell body is shifted laterally, the second hole cut and the operation of cutting and shifting is repeated until the desired number of holes have been cut. The bell body is then backed away from the ship and the hoisting hooks lowered and manipulated until they are directly in front of the cut holes. They are then pushed into these holes and the hoisting cable tautened until the hooks engage so they cannot swing out. The entire bell apparatus is then shifted along the ship's hull until a position is reached for cutting a second set of holes with the foregoing operation. The operations of shifting, cutting holes and engaging the sets of hooks is repeated until all holes are cut and all hooks engaged whereupon the bell apparatus is hoisted and the way is clear for hoisting the sunken ship.

Obviously, if it is necessary or desirable for a diver to leave the bell body this may be done as above described.

What is claimed, is:

1. In salvaging bell apparatus, a bell body, a frame surrounding said body and having the body mounted therein for lateral movement between the frame sides, supporting means for the frame, said frame having vertical and horizontal movements between said supporting means, electro-magnetic means for securing the supporting means on a ship hull, actuating means for effecting the movement of the body in the frame and for effecting the movements of the frame, and means within the bell body controlling operation of said actuating means.

2. In salvaging bell apparatus, a pair of supporting members, a vertical frame supported from said members for horizontal and vertical movements with respect to said members, a bell body carried within the frame and supported thereby for lateral movements between the frame sides, electro-magnetic means for securing said members to a ship hull, actuating means effecting the movements of the frame and bell body, and means within the bell body controlling the actuating means.

3. In salvaging bell apparatus, a pair of vertical supporting members, a carriage structure associated with each member and mounted for movement at right angles to the member, said carriage structures projecting laterally toward each other from each member, a frame having side members mounted on the projecting portions of said carriage structures for vertical movements relative thereto, said frame having top and bottom members, bell body carriages mounted in the top and bottom members and movable longitudinally thereof, a bell body fixed to said last carriages for movement therewith, actuating means for moving the carriage structures relative to the supporting members, the frame relative to the carriage structures and the bell body carriages along the frame, and means within the bell body for controlling said actuating means.

4. In salvaging bell apparatus, a pair of vertical supporting members provided at their upper and lower ends with electro-magnets for attachment of said members to a ship hull, a trackway carried by each member and extending transversely thereof to lie horizontally, a pair of carriages movable on said trackway and extending therefrom toward each other, the extending portions forming a second pair of carriages, a frame having vertical side members provided with trackways for the second pair of carriages, said frame having horizontal top and bottom members provided with trackways, a third pair of carriages movable along the last mentioned trackways, a bell body having its upper and lower ends fixed to the third pair of carriages, hydraulic jacks extending along said trackways in aligned pairs, the jacks of each pair

with trackways for the second pair of carriages, said frame having horizontal top and bottom members provided with trackways, a third pair of carriages movable along the last mentioned trackways, a bell body having its upper and lower ends fixed to the third pair of carriages, actuating means for moving said carriages, and means within the bell body for controlling said actuating means.

5. In salvaging bell apparatus, a bell body, a frame surrounding said body and having the body mounted therein for lateral movement between the frame sides, supporting means for the frame, said frame having vertical and horizontal movements between said supporting means, electro-magnetic means for securing the supporting means on a ship hull, hydraulic jacks for effecting the movement of the body in the frame, other hydraulic jacks for effecting the several movements of the frame, and valves in said bell controlling the actuation of said jacks.

6. In salvaging bell apparatus, a pair of supporting members, a vertical frame supported from said members for horizontal and vertical movements, a bell body carried within the frame and supported thereby for lateral movements between the frame sides, electro-magnetic means for securing said members to a ship hull, hydraulic jacks for effecting horizontal movement of the frame, hydraulic jacks for effecting vertical movements of the frame, other hydraulic jacks for effecting movement of the bell body in the frame, and valves in said bell body controlling actuation of the jacks.

7. In salvaging bell apparatus, a pair of vertical supporting members, a carriage structure associated with each member and mounted for movement at right angles to the member, said carriage structures projecting laterally toward each other from each member, a frame having side members mounted on the projecting portions of said carriage structures for vertical movements relative thereto, said frame having top and bottom members, bell body carriages mounted in the top and bottom members and movable longitudinally thereof, a bell body fixed to said last carriages for movement therewith, hydraulic jacks carried by the supporting members and engaging opposite sides of the carriage structures for movement of the latter on said members, hydraulic jacks carried by the frame and engaging said carriage structures for moving the frame relative to the carriage structures, other hydraulic jacks engaging the bell body carriages for moving the bell body in the frame, and valves in said bell body controlling the action of the hydraulic jacks.

8. In salvaging bell apparatus, a pair of vertical supporting members provided at their upper and lower ends with electro-magnets for attachment of said members to a ship hull, a trackway carried by each member and extending transversely thereof to lie perpendicular, a pair of carriages movable on said trackway and extending therefrom toward each other, the extending portions forming a second pair of carriages, a frame having vertical side members provided with trackways for the second pair of carriages, said frame having horizontal top and bottom members provided with trackways, a third pair of carriages movable along the last mentioned trackways, a bell body having its upper and lower ends fixed to the third pair of carriages, hydraulic jacks extending along said trackways in aligned pairs, the jacks of each pair

engaging opposite sides of a respective carriage, and valves in said bell body controlling the action of said jacks.

9. In salvaging bell apparatus, a bell body, a frame surrounding said body and having the body mounted therein for lateral movement between the frame sides, supporting means for the frame, said frame having vertical and horizontal movements between said supporting means, electro-magnetic means for securing the supporting means on a ship hull, hydraulic jacks for effecting the movement of the body in the frame, other hydraulic jacks for effecting the several movements of the frame, an oil supply sump in said bell body, a motor driven pump receiving oil from the sump, conduit means connecting the jacks in pairs of opposed units to the sump and pump, and reversing valves for selectively connecting a selected jack of each pair to the pump and the other jack of the pair to the sump.

10. In salvaging bell apparatus, a pair of supporting members, a vertical frame supported from said members for horizontal and vertical movements with respect to said members, a bell body carried within the frame and supported thereby for lateral movements between the frame sides, electro-magnetic means for securing said members to a ship hull, hydraulic jacks for effecting horizontal movement of the frame, hydraulic jacks for effecting vertical movements of the frame, other hydraulic jacks for effecting movement of the bell body in the frame, an oil supply sump in said bell body, a motor driven pump receiving oil from the sump, conduit means connecting the jacks in pairs of opposed units to the sump and pump, and reversing valves for selectively connecting a selected jack of each pair to the pump and the other jack of the pair to the sump.

11. In salvaging bell apparatus, a pair of vertical supporting members, a carriage structure associated with each member and mounted for movement at right angles to the member, said carriage structures projecting laterally toward each other from each member, a frame having side members mounted on the projecting portions of said carriage structures for vertical

movements relative thereto, said frame having top and bottom members, bell body carriages mounted in the top and bottom members and movable longitudinally thereof, a bell body fixed to said last carriages for movement therewith, hydraulic jacks carried by the supporting members and engaging opposite sides of the carriage structures for movement of the latter on said members, hydraulic jacks carried by the frame and engaging said carriage structures for moving the frame relative to the carriage structures, other hydraulic jacks engaging the bell body carriages for moving the bell body in the frame, an oil supply sump in said bell body, a motor driven pump receiving oil from the sump, conduit means connecting the jacks in pairs of opposed units to the sump and pump, and reversing valves for selectively connecting a selected jack of each pair to the pump and the other jack of the pair to the sump.

12. In salvaging bell apparatus, a pair of vertical supporting members provided at their upper and lower ends with electro-magnets for attachment of said members to a ship hull, a trackway carried by each member and extending transversely thereof to lie perpendicular, a pair of carriages movable on said trackway and extending therefrom toward each other, the extending portions forming a second pair of carriages, a frame having vertical side members provided with trackways for the second pair of carriages, said frame having horizontal top and bottom members provided with trackways, a third pair of carriages movable along the last mentioned trackways, a bell body having its upper and lower ends fixed to the third pair of carriages, hydraulic jacks extending along said trackways in aligned pairs, the jacks of each pair engaging opposite sides of a respective carriage, an oil supply sump in said bell body, a motor driven pump receiving oil from the sump, conduit means connecting the jacks in pairs of opposed units to the sump and pump, and reversing valves for selectively connecting a selected jack of each pair to the pump and the other jack of the pair to the sump.

CARL M. ZOLL.
